UNITED STATES PATENT OFFICE.

HARRISON D. MCFADDIN, OF EAST ORANGE, NEW JERSEY.

SHADE-HOLDER.

1,384,395.

Specification of Letters Patent. Patented July 12, 1921.

Application filed February 23, 1917, Serial No. 150,373. Renewed April 16, 1919. Serial No. 290,641.

To all whom it may concern:

Be it known that I, HARRISON D. MCFADDIN, a citizen of the United States, residing in East Orange, county of Essex, and State 5 of New Jersey, have invented a certain new and useful Shade-Holder, of which the following is a specification.

This invention is a shade holder and, more particularly, a holder of the type mounted 10 on a shade and adapted to resiliently grip the bulb of an incandescent lamp to adjustably support said shade directly upon the lamp.

Many of the shade holders of this general 15 type heretofore employed possess the well known disadvantage that, when the lamp is forced into the grasp of the spring clip with which said holders are provided, great care must be exercised not to push the 20 lamp into place with too much force; otherwise, the spring clip will give sufficiently to allow the projecting point of the lamp to strike against some metallic part of the shade and be broken off, with the result that 25 the lamp will be shattered. Moreover, the majority of lamp holders of this type in use require some sort of adjustment, either of a threaded member, or some other means, to lock the supporting clip to the shade, or to 30 govern the operations of said clip in maintaining the shade in any of its angular positions relative to the lamp.

With the foregoing disadvantages in mind, the object of the present invention is 35 to so construct the shade holder that, when the lamp is pressed into gripping engagement with the spring clip thereof, it will, after it reaches its proper position, be precluded by such clip from further advancement, and, accordingly, the projection at the 40 end of the lamp is safeguarded from coming into contact with the metallic portion of the holder or shade, thereby obviating the well known danger of breakage inherent in prior 45 art structures.

A further object of the invention is to so organize the holder that no adjustments whatsoever will be required, but that the holder will, at all times, automatically engage with and grip the lamp, and will, moreover, maintain the shade in any of its predetermined angular positions without any adjustment whatsoever.

Features of the invention, other than those 55 specified, as well as the advantages thereof, will be apparent from the hereinafter de-

tailed taken in conjunction with the accompanying drawing.

In the accompanying drawing, I have illustrated one practical embodiment of the 60 invention, but the construction shown therein is to be understood as illustrative, only, and not as defining the limits of the invention.

Figure 1 is an elevation of an incandescent lamp bulb, showing a shade supported 65 in position thereon by a holder embodying the present invention. In the interest of clearness, the shade is shown in central section, and part of the holder is also shown in 70 central section, the remaining part of the holder being shown in elevation.

Fig. 2 is a side elevation of the lamp bulb, showing the manner in which the spring 75 clip grips the same to maintain the shade in position. In this view, the shade and the member for securing the shade to the spring clip member are omitted.

Fig. 3 is an underneath plan view taken 80 in the plane of line 3—3 of Fig. 2, and

Fig. 4 is a detail section on the line 4—4 of Fig. 3.

Referring to the drawing, A indicates an incandescent lamp bulb, on which it is desired to mount a shade B. The shade may 85 be of any well known and conventional form, as this forms no part of the present invention. In any event, a supporting shell or thimble C is provided, with which supporting shell is associated resilient means 90 adapted to grip the lamp bulb A, further means being provided, in the form of a retaining cap D, for binding the shade to the supporting shell.

Supporting shell or thimble C is provided 95 with a portion having an upwardly tapering, frusto-conical form, on the outer converging wall of which the inner surface of shade B is adapted to rest, as shown in Fig. 1. In order to allow of the formation 100 of the shell from relatively light material, it is preferably circumferentially beaded, as at c, which bead serves to strengthen the shell against distortion. The upper end of shell C is closed and forms a seat in which 105 lies a metallic ring F of substantially the same external diameter as the inner diameter of the shell, so that said ring lies around the inner margin of the shell and in the angle formed by the sides and the closed top 110 thereof. Ring F is maintained in this position by means of tongues f, which are

stamped up from the closed end of the shell and bent over the wire ring, as clearly shown in Figs. 3 and 4.

At diametrically opposite sides of ring F, 5 and formed integral with the material from which the ring is made, is a pair of depending stem-like portions *i*, carrying at their lower ends oppositely positioned wire loops I. In the preferred embodiment of the invention, ring F, loops I and their connecting stems *i* are all formed from a single piece of wire bent into the form shown in Fig. 1. Each of the stems *i* is in the form of two parallel wires, supporting at their 10 lower ends a loop I, which is, because of the fact that it is substantially closed, of a comparatively rigid nature. Thus, the wire bent as described forms a spring clip or clamp, the stems *i*, particularly where they 15 join the loops I and the ring F, forming, in the main, the springy or resilient parts of said clamp.

The diameter of ring F, from which loops I depend, is somewhat less than the greatest 20 diameter of the lamp bulb A, so that, when the bulb is introduced between said loops and pressed into the position shown in Fig. 2, the loops are forced apart and the clip thereby placed under tension. This tension 25 is sufficient to cause the lamp bulb A to be tightly gripped between the loops for the purpose of maintaining supporting shell C in position on said bulb. However, as the loops I are substantially circular, they may 30 be shifted about upon the outer periphery of the bulb to bring supporting shell C into various desired angles of inclination relative to the lamp.

A salient feature of the invention resides 35 in the fact that, after the bulb has been forced into the position shown in Fig. 2, each of the loops I embraces a portion of the convex surface of the bulb, and a portion of said surface extends through and 40 beyond each loop. Thus, the portion of each loop adjacent its stem *i* forms, in effect, a shoulder *i'*, against which shoulders the curvilinear surface of the bulb comes to seat, upon introduction into the grip of the spring 45 clip. Said two shoulders *i'* of loops I thus engage with the upper portion of the bulb comparatively near its center, and great pressure would be necessary to force the lamp any farther into the spring clip after 50 the bulb has come into engagement with said shoulders, as it would be necessary to expand the spring clip on a comparatively short radius. For this reason, during the operation 55 of introducing the lamp into the grip of the spring clip, the operator is safeguarded against forcing the lamp too far into the clip, or to such distance that the projecting point at the end of the lamp 60 would come into engagement with the me-

tallic shell and cause the breaking of the 65 lamp. This safeguarding of the lamp is due, to a considerable extent, to the fact that loops I are substantially rigid, and are not adapted to expand or bend open to allow of 70 forward movement of the lamp, as has generally been the practice in the prior art.

When the shade B is positioned with its upper portion resting upon the upwardly converging, frusto-conical portion of supporting shell C, it is locked in rigid engagement by means of the retaining cap D, which is provided centrally with a depending, threaded stem *d*, adapted to screw into a threaded tap positioned centrally of the closed end of the supporting shell. Retaining cap D is in the form of a dished shell of sufficient size to close the open top of the shade, while the lateral edges of said cap are adapted to engage with the outer surface of said shade so that, when the cap 85 is screwed down tightly, it forces the shade to a firm seat upon the frusto-conical portion of the supporting shell. Retaining cap D is preferably provided with ventilating openings *d'*, while the openings *c'*, formed 90 in the closed end of the supporting shell by the stamping out of portions of said shell to form the tongues *f*, serve as ventilating openings in the shell.

It will be manifest from the foregoing description that the shade B is supported upon lamp A without the necessity of any means which requires adjustment, either to lock the shade in any predetermined position relative to the lamp, or to govern the angular inclination of said shade relative to the axis of said lamp. The strength of the clip is such, and the parts are so nearly-balanced, that the shade will, of itself, and through the clamping of the clip, retain any desired 100 angular position.

Having thus fully described the invention, what I claim as new, and desire to secure by Letters Patent, is:

1. A shade holder embodying an inverted 110 frusto-conical thimble on which a lamp shade is adapted to be seated, means for detachably holding the lamp shade to the thimble to permit of a change of shades, a pair of spaced loops positioned beneath the thimble 115 and each of which is provided with a pair of upwardly extending resilient stems with the stems of each pair parallel to one another and contacting with one another throughout substantially their entire length 120 and the upper ends of the corresponding stems of each pair being connected with one another by a substantially semi-circular portion, which is seated in the base of the thimble, and tongues stamped up from the thimble and bent over the semi-circular portions 125 for securing them firmly to the thimble, whereby said loops are resiliently mounted

upon the thimble and are adapted to embrace and resiliently grip the lamp bulb forced between the loops.

2. A shade holder embodying an inverted frusto conical thimble on which a lamp shade is adapted to be seated, and means for detachably binding the lamp shade to the thimble to permit of a change of shades, in combination with a lamp gripping member 5 formed from a single length of wire bent to 10 form semicircular portions seated in the base

of the thimble and from the termini of which semicircular portions depend resilient stems carrying at their bottoms oppositely positioned substantially parallel loops, 15 whereby said loops are each supported on two resilient stems, and means for securing the semicircular portions of the wire to the thimble.

In testimony whereof I have signed my 20 name to this specification.

HARRISON D. McFADDIN.
